UNITED STATES PATENT OFFICE.

HENRY F. MAUPAI, OF BROOKLYN, NEW YORK, ASSIGNOR TO SACKETT & WILHELM'S CORPORATION, OF BROOKLYN, NEW YORK, A CORPORATION OF NEW YORK.

DISPLAY DEVICE FOR BOTTLES AND THE LIKE.

Application filed April 24, 1924. Serial No. 708,637.

To all whom it may concern:

Be it known that I, HENRY F. MAUPAI, a citizen of the United States, and a resident of New York, borough of Brooklyn, in the 5 county of Kings and State of New York, have invented certain new and useful Improvements in Display Devices for Bottles and the like, of which the following is a specification.

10 This invention relates to display devices and particularly to such devices of the class specified as are adapted for erection on the necks of bottles or the like.

15 The object of my improvements is to provide a display device of the character specified of simple construction and having features of strength and rigidity over similar devices known to me.

20 To these ends my improvements comprise features illustrated in their preferred embodiment in the drawing accompanying this specification, wherein:

25 Figure 1 is a perspective elevation of my improved device erected in display position on a bottle. Fig. 2 is a plan view of my device spread out flat. The scale of Fig. 1 is about three-eighths size and that of Fig. 2 is about one-half size.

30 While it is recognized that several types of display devices adapted for erection on bottles are known, none which are known to me have side-wing members interlocking with the body of the display and by which construction great rigidity and strength are 35 imparted to the device whereby its life is prolonged and whereby a neat and trim appearance is maintained.

30 My improved device comprises display member 2, which may have a decorative contour, as shown. Formed partly from the lower portion of display member 2, Fig. 2, and projecting therebelow are flaps 3 and 4. Upper flap 3 is preferably formed entirely from display member 2 and is articulated 45 thereto along transverse line 5. Said flap 3 has opening 6 therethrough, usually circular in shape and located about in the middle of said flap. Said flap preferably terminates downwardly within the lower margin of display member 2 and is articulated to flap 4 therebelow, along transverse line 7. Flap 4 is preferably of greater vertical height than flap 3 and has opening 8 therethrough, preferably of oval shape, the long 55 way of said oval hole being vertical, Fig. 2.

Extending oppositely from flap 4 are wings 9, 10, respectively, preferably triangular in shape and each is provided in the lower portion thereof with a short slot 11 therethrough for interlocking engagement with short ears formed from display member 2, presently to be described. Said wings 9, 10 are hingedly connected to flap 4 along its opposite edges 12, 13, respectively. Said edges are preferably vertical and parallel.

Cut out from opposite sides of flaps 3, and inreaching toward each other below opening 6 of said flap, are opposite ears 14, 15, respectively, integral with display member 2. These ears are adapted for interlocking with slots 11, 11, respectively, when the device is erected in display position.

In erecting the device wings 9, 10 are folded backwardly, flap 3 upwardly and flap 4 downwardly and slots 11, 11 slipped over ears 14, 15, respectively, whereby flaps 3, 4 are held rigidly in place relatively to display member 2 and wings 9, 10 form box-like sides to the triangular structure thus erected. The device may then be placed on the bottle, Fig. 1, where it will be rigidly sustained in display position, the edges of openings 6 and 7 engaging the neck of the bottle.

I claim:

1. In a display device of the character described the combination of a display member, a flap formed from the lower portion of said display member and articulated at its upper edge thereto, a second flap articulated to the lower edge of said first flap, said flaps being provided with means for engaging a bottle on which the device is erected, and opposite wings articulated to the side edges of said second flap, said display member having opposite inreaching ears and said wings being adapted to engage said ears respectively.

2. In a display device of the character described the combination of a display member, a flap formed from the lower portion of said display member and articulated at its upper edge thereto, a second flap articulated to the lower edge of said first flap, an opening in each of said flaps the edges of which are adapted for engagement with a bottle on which the device is erected, opposite wings articulated to the side edges of said second flap, said display member having opposite inreaching ears, and means on said

- wings for interlocking with said ears respectively.
3. In a display device of the character described the combination of a display member, a flap formed from the lower portion of said display member and articulated at its upper edge thereto, a second flap articulated to the lower edge of said first flap, an opening in each of said flaps the edges of which are adapted for engagement with a bottle on which the device is erected, opposite wings articulated to the side edges of said second flap, said display member having opposite inreaching ears cut from within the rec-
- 5 tangle of said first mentioned flap and below the opening therethrough, and a slot through the lower portion of each of said wings, said slots being adapted for inter-
- 10 locking with the inreaching ears of said display member.
4. In a display device of the character described the combination of a display member, a plurality of flaps one of which is articulated to said display member and another hingedly connected to said first flap, 25 opposite wings articulated to the side edges of one of said flaps, said display member having opposite inreaching ears and said wings being adapted to engage said ears respectively, and means on said device for engagement with a bottle on which the device is erected.
